UNITED STATES PATENT OFFICE.

FRED RAMSAY MASON AND THOMAS FITZPATRICK, OF RONAN, MONTANA.

MACHINE FOR REMOVING RAILS AND EXTRACTING SPIKES.

Application filed June 29, 1921. Serial No. 481,360.

To all whom it may concern:

Be it known that we, FRED RAMSAY MASON and THOMAS FITZPATRICK, citizens of the United States, and residents of Ronan, in the county of Missoula and State of Montana, have invented certain new and useful Improvements in Machines for Removing Rails and Extracting Spikes, of which the following is a specification.

10 The present invention relates to machines for removing and taking up rails from railway tracks and extracting spikes, and has for its object to provide a machine of this character which when drawn along by any 15 available tractor such as a locomotive or the like, automatically lifts the rails from the ties or roadbed and extracts the spikes, which carries out this operation speedily and without distortion of the rails, and which 20 is in general of simple and durable construction, reliable in operation and easy and inexpensive to manufacture and operate.

Other objects and advantages of the invention reside in certain novel features of 25 construction, combination and arrangement of parts which will be hereinafter more fully described and particularly pointed out in the appended claims, reference being had to the accompanying drawings forming part 30 of this specification, and in which:

Figure 1 is a fragmentary view in side elevation of the machine embodying the invention;

Figure 2 is a similar view in plan;

35 Figure 3 is a view in section, on line 3—3 of Figure 2;

Figure 4 is a similar view on line 4—4 of Figure 2; and

Figure 5 is a detail perspective view of 40 the combined shoe and spike holder employed at the forward end of the machine.

Referring to the drawings wherein for the sake of illustration is shown the preferred embodiment of the invention, the number 45 10 designates the combined rail lifters and spike extractors, which are of identical construction and each of which includes a pair of channel irons 11, the channel irons being arranged in parallel relation to each 50 other and having their lateral flanges extending away from each other, as shown in Figure 4. The channel irons of each lifter and extractor and the lifters and extractors themselves are connected with each other 55 and organized into a unitary machine by means of cross bars 12 and cross braces 13

extending between and secured to the channel bars as clearly illustrated in Figure 2. A pair of lifter bars 15 is carried by each pair of channel bars 11, the lifter bars extending upwardly and rearwardly of the forward end of the channel bars and being secured by fastening devices 16 to the flat faces of the channel bars. The lifter bars of each pair extend parallel to each other 60 and their adjacent lateral faces are slightly spaced from each other whereby the lifter bars are adapted to accommodate between them the web of the rail R, the ball or head of the rail being engaged on its underside 65 by the top surfaces of the lifter bars, as will be hereinafter more fully described.

At the forward end of the machine combined shoe and spike holders designated generally at 20 are secured by means of fastening devices 21 to the outer member of each pair of channel bars. The combined shoe and spike holders each comprises a body portion of angular form having an upwardly inclined extension 22 at its forward end 70 whereby the shoes lift the machine over the ties of the roadway. The side edge of the extension 22 adjacent the rail is inclined and beveled, as designated at 23, and is adapted to engage the heads of such spikes as may be 75 slightly disengaged from the base of the rail so as to force them into position against the base of the rail to prevent their shearing off.

Rail carriers designated generally at 25 80 are provided at the rear of the machine and each includes a pair of parallel bars 26 secured at one end to the channel bars 11 and extending upwardly and rearwardly from the machine and supported at their outer 85 ends by means of a truss rod 27 secured at one end, as at 28, to one of the cross bars 12 and at its other end, as at 29, to the rail carrier, a stanchion 30 supporting the truss rod intermediate its ends and turn buckles 100 31 being provided for suitably tensioning the truss rod 27. Each rail carrier includes a plurality of brackets 32 for maintaining the bars 26 thereof in spaced relation and at regular intervals there is provided rollers 105 33 rotatably journaled in the bars 26 and upon these rollers the rails are supported as they are delivered to the carriers from the machine. A draw head 35 is connected with the forward end of the machine by means of 110 channel irons 36 or the like, the draw head having an eye 37 or other suitably connect-

ing means whereby it may be coupled with the tractor such as a locomotive or the like for operating the machine.

Spike receivers 40 are arranged at the rear of each of the combined lifters and spike removers and are adapted to receive the spikes when they drop from the rails after the extracting operation.

In the use of the machine, it is placed upon the track to be taken up and the lifter bars 15 have their forward beveled ends engaged beneath the heads of the rails. The machine is then coupled by means of the draw head 35 with its tractor and is drawn along the track. As it moves along the track the lifter bars 15 engage beneath the rail heads, and as these lifter bars are inclined upwardly and rearwardly they lift the rails upwardly from the track and extract or draw the spikes out of the ties, the spikes being lifted up between the channel bars as shown to the right in Figure 4. The rails and spikes pass through the channel bars and the rails are delivered to the rail carrier 25 and the spikes to the spike receivers 40. In this manner the rails are removed from the tracks and the spikes are extracted in a single operation which is continuous and efficient. Moreover, the rails are not distorted since they are received upon the rail carrier 25 and supported thereon whereby the metal of the rails is not subjected to excessive strains although the resiliency of the metal thereof is brought into play during the action.

It is obvious that the machine may be constructed for use with any gauge of track or any weight of rail and will efficiently pull spikes of any length. Again the machine is efficient on either straight tracks or curves. It requires little or no attention and carries out the operation of removing and lifting the rails and extracting the spikes automatically, it being simply necessary to draw the machine along the track as described. It is to be noted that during the initial phase of the spike pulling operation the spikes are engaged by the beveled and inclined surfaces 23 of the combined shoe and spike holder, whereby these spikes are held against the rails and prevented from shearing off until they are received between the channel bars, at which time the channel bars take up the function of this inclined surface 23. The upwardly inclined extension 22 of the shoe precludes against any interference of the forward motion of the machine as these shoes ride up over obstructions and over the ties and thus facilitate the advance of the machine, the lower lateral flange of the channel bars affording slide surfaces or runners for carrying the machine.

It is obvious that roller bearings, caterpillar tread, or wheel bearings having a wide

radius may be substituted as equivalent elements for the sliding channel irons within the purview of the present invention; and similarly that the rail lifters might comprise rows of projections in lieu of the continuous bars or a grapple taking the form of a C with its open side disposed downwardly so as to accommodate the web of the rail.

While we have shown and described the preferred embodiment of our invention, various changes in the minor details of construction may be made without departing from the invention as defined in the appended claims.

We claim:

1. In a machine for removing rails and extracting spikes, pairs of channel bars, cross bars and cross braces extending between and secured to said channel bars, upwardly and rearwardly inclined lifter bars carried by said channel bars and arranged in spaced and parallel relation and adapted to engage beneath the head of the rails to be removed, combined shoes and spike holders carried at the forward end of the machine, spike receivers arranged at the rear of the machine, rail carriers extending upwardly and rearwardly from the machine, means for supporting said rail carriers, a draw head, and channel irons connecting said draw head and said machine.

2. In a machine for removing rails and extracting spikes, pairs of channel irons, means for securing said channel irons in spaced and parallel relation, inclined lifter bars carried by said channel irons and adapted to engage the rails to be lifted, rail carriers extending upwardly and rearwardly from said channel irons and each including spaced and parallel bars and rollers journaled in said bars, and means for supporting said rail carrier including a truss rod and a stanchion supporting said truss rod.

3. In a machine for removing rails and extracting spikes, pairs of channel irons, means for securing said channel irons in spaced and parallel relation, inclined lifter bars carried by said channel irons and adapted to engage the rails to be lifted, rail carriers extending upwardly and rearwardly from said channel irons and each including spaced and parallel bars and rollers journaled in said bars.

4. In a machine of the character described, a pair of channel bars, inclined lifter bars carried by said channel bars, a rail carrier including a pair of longitudinal bars carried by the channel bars and having rollers for supporting the rails.

5. In a machine of the character described, a pair of channel bars, lifter bars carried by said channel bars, and a rail carrier associated with said channel bars.

6. In a machine for removing rails and

- extracting spikes, channel bars, inclined lifter bars carried by said channel bars and engageable beneath the head of the rail to be removed whereby said rail is lifted upwardly from the roadbed when said channel bars are advanced, and said spikes are extracted and carried through said channel bars, and spike receivers arranged at the rear end of said channel bars.
- 10 7. In a machine for removing rails and extracting spikes, channel bars, inclined lifter bars carried by said channel bars and engageable beneath the head of the rail to be removed whereby said rail is lifted upwardly from the roadbed when said channel bars are advanced, and said spikes are extracted and carried through said channel bars.
- 15 8. In a machine for removing rails and extracting spikes, channel bars, inclined lifter bars carried by said channel bars and engageable beneath the head of the rail to be removed whereby said rail is lifted upwardly from the roadbed when said channel bars are advanced and said spikes are extracted and carried through said channel bars, and
- 5 a rail carrier for receiving the rails as they are removed.
9. In a machine of the character described, a pair of channel bars, lifter bars carried by said channel bars, a rail carrier carried by said channel bars, and a draw head associated with said channel bars and adapted to advance the machine.
- 10 10. In a machine of the character described, a pair of channel bars adapted to span the rail, and a pair of inclined lifter bars carried by the channel bars and engageable with the underside of the tread of the rail.
- 15 11. In a machine of the character described, a frame adapted to be advanced along a railway track, and a pair of inclined lifter devices carried by the frame and engageable with the under side of the tread of the rail whereby as the frame is advanced along the track the lifter devices will effect lifting of the rails and extracting of the spikes securing the same in position.

FRED RAMSAY MASON.
THOMAS FITZPATRICK.
